Primary Examiner — Kelley A Donnelly(74) *Attorney, Agent, or Firm* — Dean Craine; Marisa Whitaker(57) **CLAIM**

The ornamental design for a breakfast tray, as shown and described.

DESCRIPTION

FIG. 1 is a top front perspective view of breakfast tray showing my new design in an unfolded configuration.

FIG. 2 is a front elevational view thereof, the rear elevational view being a mirror image thereof.

FIG. 3 is a top plan view thereof.

FIG. 4 is a bottom plan view thereof.

FIG. 5 is a left-side elevational view thereof, the right-side elevational view being a mirror thereof.

FIG. 6 is a sectional view taken along line 6-6 in FIG. 3.

FIG. 7 is a top front perspective view of the breakfast tray in a folded configuration.

FIG. 8 is a top plan view thereof.

FIG. 9 is a bottom plan view thereof; and,

FIG. 10 is a sectional view taken along line 10-10 in FIG. 8.
